UNITED STATES PATENT OFFICE.

EDSON F. GALLAUDET, OF DAYTON, OHIO.

DESIGN FOR A CANDLESTICK.

No. 37,559.

Specification for Design.

Patented Sept. 19, 1905.

Application filed July 27, 1905. Serial No. 271,548. Term of patent 3½ years.

To all whom it may concern:

Be it known that I, EDSON F. GALLAUDET, a citizen of the United States, residing at Dayton, in the county of Montgomery and State of Ohio, have invented a new and original Design for a Candlestick, of which the following is a specification, reference being had to the accompanying drawing, forming part thereof.

The figure is a perspective view of a candlestick, showing my new design.

I claim—

The ornamental design for a candlestick, as shown.

EDSON F. GALLAUDET.
